UNITED STATES PATENT OFFICE.

WILLIAM HUMPHREY PERRIN, OF NEW LISKEARD, ONTARIO, CANADA.

SHEAF-SHOCKER.

1,105,999.

Specification of Letters Patent.

Patented Aug. 4, 1914.

Application filed July 22, 1912. Serial No. 710,833.

To all whom it may concern:

Be it known that I, WILLIAM HUMPHREY PERRIN, a subject of the King of Great Britain, residing at New Liskeard, in the 5 Province of Ontario, Dominion of Canada, have invented certain new and useful Improvements in Sheaf-Shockers, of which the following is a specification.

My invention relates to improvements in 10 sheaf shockers of the type in which the sheaves in discharging from the binder deck are up-ended and caught by a collecting member having rotating radial arms, which arms are adapted to simultaneously release 15 said sheaves at a given point and permit them to drop in the form of a shock.

The invention involves further, improvements and developments of my earlier invention disclosed in United States Patent 20 806,283 granted Dec. 5th, 1905, and certain improvements on my United States Patent No. 999,251 granted August 1st, 1911.

The objects of the invention are firstly: to provide an effective form of support and 25 guide for the sheaf during its passage from the up-ending mechanism to the collecting member; secondly: to assist the support of the first sheaf of each shock which is caught on the collecting member; thirdly: to provide more effectual means for supporting the inner side of the sheaf which means will release automatically at the moment of discharge and will be moved clear of the discharging sheaf; fourth: to enable the device 35 to be tripped in order to drop the sheaf slightly before its ordinary time; fifthly: to provide hand controlled means to drop the sheaves when the shock is completed; sixthly: to construct a device having means 40 for discharging the sheaves in a slightly forward direction and other objects hereinafter described.

The invention consists of the parts hereinafter more particularly described and 45 illustrated in the accompanying drawings in which:—

Figure 1 is a perspective view of the device constructed according to my invention showing a portion of the binder deck and 50 knotting mechanism as well as the shocking mechanism. Fig. 2 is a plan view of the shocking mechanism. Fig. 3 is a side view of a portion of the shocking mechanism showing the means for rotating the radial 55 arms and means for operating the same. Fig. 4 is a vertical section of the gear on

the collecting member to which one set of the radial arms are connected also showing the mechanism for tilting the same to throw the sheaves forming the shock in a slightly 60 forward direction. Fig. 5 shows details of the mechanism for operating the arms. Fig. 6 is a plan view of the gear to which the upper set of radial arms are connected. Fig. 7 is a side view of a plate suspended from a 65 sleeve. Fig. 8 is a vertical section of a portion of the support on which a cross shaft having a pinion at its outer end meshing with the aforesaid gear is mounted. Fig. 9 is a vertical section of the gear on the collecting member showing the operation of the 70 tilting mechanism. Fig. 10 is a section showing the relative mounting of the power shaft to the plate and spindle.

Like characters of reference indicate corresponding parts in each of the figures.

1 is the deck of the binder, and 2 is a horizontal knotter shaft suitably mounted thereon.

3 is a disk mounted thereon and 4 is a 80 discharge arm pivotally connected thereto.

5 is a sleeve surrounding the shaft 2 and 6 is a suitable support mounted thereon.

7 is a gear mounted on the shaft 2 and having the extending portion 8, and 9 is a 85 discharge arm pivotally connected to the portion 8.

10 is a forked portion pivotally connected to the support 6 and having an end 10^a to which a spring 11 is attached at the end, 90 the other end of the spring being attached to the support, said forked portion 10 being held normally down against the deck 1.

12 is a depending portion pivotally connected to the outer end of one of the prongs 95 of the forked portion.

13 is a follower member located at substantially the end of the binder deck, to support and guide the sheaves, said member being formed of a thin plate of metal having 100 the end 14 inclined in a stubbleward direction, and suitable means is provided to raise the member 13 into position to support the head of the sheaf, said means consisting of an arm 15 pivoted to a bracket 16 on the 105 frame, said arm being adapted to be raised and lowered at the proper point by a cam 17 carried on a shaft 18 on the knotter mechanism and adapted to engage a roller 19 on the arm 15.

20 is a radially extended flexible plate, preferably of spring metal to give additional

- support to the first sheaf on the collecting member.
- 21 is a shaft extending in a vertical direction having the bevel pinion 22 at its lower end meshing with the aforesaid gear 7.
- 23 is a bevel gear at the top of the shaft 21 meshing with a bevel gear 24 on a horizontal shaft 25.
- 26 is a sleeve surrounding the shaft 25 and
- 10 27 is a casting connected to inner end of the sleeve and rigidly securing the same to the support 6.
- 28 is a pinion on the outer end of the shaft 25 meshing with a gear 29 to the underneath side of which the upper set of radial arms 30 are connected.
- 31 is a circular plate situated above the gear 29 and rigidly secured to the sleeve 26 by the inverted U-bolts 32.
- 20 33 are lugs on the top of the plate extending up through a cut-away portion of the sleeve and having apertures therein through which the shaft 25 extends.
- 34 is a raised portion formed at the periphery of the plate constituting a cam-shaped indenture, and 35 is a block designed to be secured in one end of the indenture.
- 36 is a vertical spindle extending up through the gear 29 and plate 31 and having
- 30 a head 37 with an aperture therein, said head extending up through the plate between the two lugs 33, the shaft 25 also extending through the aperture in the head 37.
- 38 is a collar pinned to the vertical spindle
- 35 36 for holding the gear 29 in place, but allowing it to rotate relatively to the spindle.
- 39 is a spider having a central collar 40 surrounding the spindle 36 but independent thereof, the lower radial arms 41 being secured thereto.
- 42 is a horizontal member (Fig. 5) having a forked end 43 extending around the spindle, and abutting the collar 40, the opposite end 44 of the member 42 is turned upwardly.
- 45 45 is a link connection between the member 42 and the gear 29 for holding the former in place on the vertical spindle.
- 46 is a pin extending through an aperture
- 50 47 in the gear 29; the upper and lower ends of the pin abut the lower surface of the plate 31, and upwardly turned end 44 of the member 42 respectively.
- 48 are inwardly turned hooks pivoted to the lower ends 49 of the upper arms 30 and
- 55 50 are the slightly downwardly turned ends of the lower arms 41.
- 51 are lugs formed therein.
- 52 are rods pivotally connected to the hooks 48 and the lugs 51.
- 60 53 are outwardly turned hooks.
- 54 are depending arms pivotally connected to each of the upper arms 30 and at the bottom pivotally connected to the inner ends of the hooks 53.
- 65 55 are depending arms each having a slot
- 56 near its upper end and 57 is a pin extending through the slot and connecting each arm 55 to the lower arm 41, the lower end of each arm 55 being pivotally connected to each hook 53 intermediately of the length 70 of the same.
- 58 is a curved plate or brace pivotally connected to each of the arms 41 and 54 respectively.
- 59 is a track surrounding the gear 29 and
- 75 having the indented cam-shaped surface 60 therein.
- 61 is a curved rocker arm suitably curved to extend over the plate 31 and pivoted near one side in the bearing 62. 63 is a lever for 80 operating said rocker.
- 64 and 65 are the short and long ends of the rocker 61 turned downwardly and designed to bear against the track 59.
- 66 is a downwardly curved projection secured to the plate 31 and also designed to bear against the track 59.
- The operation of the machine is as follows:—The sheaves slide down the deck of the binder, and the discharge arms 4 and 9 rotating force the same down between the forked member 10 and the edge of the binder deck. The hook 48 on the lower end 49 of the arm 30 catches the twine surrounding the sheaf. The discharge arm 9 forces the head of the sheaf upward while the discharge arm 4 drops and the member 10 holds the butt down and its bearing against the plate 12, gradually turns same into a horizontal position as the sheaf is up-ended 100 when the plate loses its grip. The prong 10^b on account of its peculiar curvature aids this up-ending as do the plates 13 and 20. The sheaf then being up-ended is also grasped by the hook 53 and the collecting 105 member rotates until the next pair of arms come into position when the operation is repeated. These operations continue until the collecting member is full when the pin 46 comes under the raised cam surface 34 in 110 the plate 31 when the pin is permitted a certain amount of vertical play. This allows the forked end of the member 42 to drop and the spider 39 carrying the lower arms 41 drops thus forcing the depending 115 arms 54 and 55 backward depressing the hooks 53 out of engagement with the sheaves at the same time forcing the rods 52 down disengaging the hooks 48. Thus the sheaves are released and drop into the form of a 120 shock.
- The collecting member is driven from the knotter shaft 2 as follows:—The shaft is provided with a bevel gear 7 which meshes with a bevel gear 22 on a shaft 21 which also carries at the top a bevel gear 23 which meshes with a bevel gear 24 on the inner end of the shaft 25, the outer end of the shaft being provided with a pinion 28 meshing with the gear 29 on the shocking mechanism 125
- 130

which rotates the arms and revolves the member 42 and the pin 46. It is to be understood however that the shocking mechanism may be driven by any suitable means.

5 The actuating thereof and dropping of the sheaves as described above is automatic, but it is found desirable to provide hand controlled means for actuating same, and for this purpose the rocker 61 is provided having the short and long ends 64 and 65 respectively which bear against the track 59. The lever 63 actuates the rocker. The same is inoperative until the indented cam surface 60 in the track 59 comes opposite the projection 66 which occurs after the collecting member is full of sheaves. The block 35 is inserted in the cam surface 34 in order that the pin 46 will not automatically trip the arms, the pin resting on the said block. 10 When the gear is in the position described the same is tilted backwardly by turning the lever 63 over, inclining the sheaves forwardly. The tilting of the gear allows the pin 46 some play and the forked end of the member 42 drops a requisite extent, thus lowering the arms 41 which disengages the hooks from the sheaves, allowing the same to drop in the form of a shock. The hand operating means are provided to deposit 15 the shock just before turning a corner or just after a corner is turned. It is desirable to have the shocks all in a straight row and if the discharge were allowed to take place while the machine was turning the corner the shock would be out of its proper alignment. Should the operator not use the lever for releasing the sheaves, the first movement of the shaft 2 will cause the pin 46 to drop into the raised cam surface 34 thus releasing 20 the sheaves.

40 What I claim as my invention is:

1. In a sheaf shocker and in combination, a binder having a binder deck, a sheaf collecting member supported adjacent to the binder deck and to the rear thereof having means adapted to catch the discharged and up-ended sheaves, a follower member located near the edge of the binder deck movable upwardly as a whole from the binder deck and having means to support the stubbleward side of the head of each sheaf while passing from the discharging and up-ending mechanism to the sheaf collecting member, and means for raising said member. 45

50 2. In a sheaf shocker and in combination, a binder having a binder deck, a sheaf collecting member supported adjacent to the binder deck and to the rear thereof having means adapted to catch the discharged and up-ended sheaves, a follower member located near the edge of the binder deck movable upwardly as a whole from the binder deck and having means to support the stubbleward side of the head of each sheaf 55 while passing from the discharging and up-

ending mechanism to the sheaf collecting member, a pivoted arm supporting the follower member and connected to the collecting member, a cam operatively connected to the arm in such position that when rotated it will raise the arm, and a drive shaft supporting the cam. 70

3. In a sheaf shocker and in combination, a binder having a binder deck, a sheaf collecting member supported adjacent to the binder deck and to the rear thereof having means adapted to catch the discharged and up-ended sheaves, a follower member located near the edge of the binder deck in the form of a curved plate having an end flared in a stubbleward direction and movable upwardly as a whole from the binder deck and having means to support the stubbleward side of the head of each sheaf while passing from the discharging and up-ending mechanism to the sheaf collecting member, and means for raising said member. 75

4. In a sheaf shocker and in combination, a binder having a binder deck, a sheaf collecting member supported adjacent to the binder deck and to the rear thereof having a plurality of radial arms with means for retaining the sheaves thereon, central supporting means, and a supporting plate carried by one of the arms extending inwardly therefrom and adapted to form an abutment 95 for the sheaves. 90

5. In a sheaf shocker and in combination, a binder having a binder deck, a sheaf collecting member supported adjacent to the binder deck and to the rear thereof having a plurality of radial arms with means for retaining the sheaves thereon, central supporting means and a supporting plate carried by one of the arms formed of flexible sheet metal and extending inwardly to form an abutment for the sheaves. 100

6. In a sheaf shocker and in combination, a binder having a binder deck, a supporting frame rotatable about a vertical axis supported adjacent to the binder deck, a set of fork members adapted to engage one side of each of the sheaves as they are discharged, a second set of hook members adapted to engage the other side of the sheaves, means for simultaneously actuating the hook members to discharge the sheaves, and means for simultaneously swinging the inner set of hooks inwardly during discharge. 115

7. In a sheaf shocker and in combination, a binder having a binder deck, a set of fork members supported adjacent to the binder deck and to the rear thereof adapted to engage the sheaves on one side, a second set of fork members extending around the first set adapted to engage the other sides of the sheaves, each of said outer fork members including a radial arm and a hook pivoted thereto and means for simultaneously 125 130

swinging all the hooks downwardly, and each of the inner fork members including an arm supported from the arm of the outer fork members, a hook and means connecting the hook with the operating means for the fork on the outer member to cause it to operate in unison therewith.

8. In a sheaf shucker and in combination, a binder having a binder deck, a set of hook members supported adjacent to the binder deck and to the rear thereof adapted to engage the sheaves on one side, a second set of hook members extending around the first set and adapted to engage the opposite sides of the sheaves, each of said outer hook members including a radial arm and a hook pivoted thereto and means for simultaneously swinging all the hooks downwardly, and each of the inner hook members including an arm supported from the arm of the outer hook members, a hook and means connecting the hook with the operating means for the hook on the outer member to cause the same to operate in unison therewith, and a link connecting said last mentioned arm with a moving part of the operating mechanism to cause the arm to swing inwardly during discharge.

9. A sheaf shucker of the character described having means for up-ending the discharging sheaves, a binder having a binder deck, a rotatable collecting member supported by and located stubbleward of the binder deck and having hook members for engaging the sheaves as they are discharged, means for simultaneously operating the hook members to discharge the sheaves arranged normally to trip at a determined point, and manually operable means for tripping the discharging mechanism a short time before its normal time.

10. In a sheaf shucker and in combination, a binder having a binder deck, a rotary sheaf collecting member supported by and

located stubbleward of the binder deck having means for retaining the sheaves therein, a hook member, and manually controlled means for tilting the hook member in a forward direction and discharging same in this direction.

11. In a sheaf shucker and in combination, a binder having a binder deck, a rotary sheaf collecting member supported by and located stubbleward of the binder deck having means for retaining the sheaves therein, a hook member, manually controlled means for tilting the hook member in a forward direction and discharging same in this direction, and automatic means for discharging the sheaf when the manual means is not operated.

12. In a sheaf shucker and in combination, a binder having a binder deck, a sheaf collecting member freely mounted on a vertical spindle supported by and located stubbleward of the binder deck, driving means for rotating the collecting member, a gear on the driving means, a gear on the collecting member meshing with a gear on the driving means, a track on the gear portion on the collecting member, a plate, a sleeve surrounding the driving shaft, said plate being suitably secured to the sleeve, said track on the gear having an indented cam surface portion, a projection bearing against the track, a rocker arm pivotally connected to the plate and having the ends bearing against the track, and a lever for operating the rocker arm tilting the gear when the projection is above the indented cam shaped surface.

In witness whereof I have hereunto set my hand in the presence of two witnesses.

WILLIAM HUMPHREY PERRIN.
